US0D1017170S

(12) **United States Design Patent** (10) **Patent No.:** **US D1,017,170 S**
(45) **Date of Patent:** **** Mar. 5, 2024**

(54) **ELECTRONIC WASHING MACHINE**

(71) Applicant: **LG ELECTRONICS INC.**, Seoul (KR)

(72) Inventors: **Junghwan Lee**, Seoul (KR); **Sojin Park**, Seoul (KR); **Eunyoung Chee**, Seoul (KR); **Hyewon Kim**, Seoul (KR)

(73) Assignee: **LG ELECTRONICS INC.**, Seoul (KR)

(**) Term: **15 Years**

(21) Appl. No.: **29/802,164**

(22) Filed: **Aug. 3, 2021**

(30) **Foreign Application Priority Data**

Feb. 10, 2021 (KR) 30-2021-0007269

(51) **LOC (14) Cl.** **15-05**

(52) **U.S. Cl.**

USPC **D32/6**

(57) **CLAIM**

The ornamental design for an electronic washing machine, as shown and described.

DESCRIPTION

FIG. 1 is a front perspective view of the electronic washing machine showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use of the claimed design.

(Continued)

The broken lines depict portions of the electronic washing machine that form no part of the claimed design.

1 Claim, 8 Drawing Sheets
